United States Patent Office.

JOHN MARTINO, JACOB BEESLEY, AND JOHN CURRIE, OF PHILADELPHIA, PENNSYLVANIA,
ASSIGNORS TO STUART, PETERSON & CO., OF SAME PLACE.

Letters Patent No. 63,646, dated April 9, 1867.

IMPROVEMENT IN HEATING STOVES.

The Schedule referred to in these Letters Patent and making part of the same.

TO ALL WHOM IT MAY CONCERN:

Be it known that we, JOHN MARTINO, JACOB BEESLEY, and JOHN CURRIE, all of Philadelphia, Pennsylvania, have invented certain Improvements in Stoves; and we do hereby declare the following to be a full, clear, and exact description of the same, reference being had to the accompanying drawing, and to the letters of reference marked thereon.

Our invention relates to improvements in that class of cheap stoves in which the body or fire-pot is made of cast iron, and of an oval or egg shape, and into which the fuel is introduced from the top; and our improvements consist of a cast-iron body or fire-chamber, surmounted with a cap, and the latter with a cylindrical casing containing an oven, so that the entire stove is an economical disseminator of heat, and a cheap and serviceable cooking stove for small families, for the cabins of vessels, and for other places where a more costly stove would be out of place.

In order to enable others skilled in the art to make and use our invention, we will now proceed to describe its construction and operation. On reference to the accompanying drawing, which forms a part of this specification—

Figure 1 is a front view of our improved stove.

Figure 2, a vertical section on the line 1-2, fig. 1.

Figure 3, a vertical section on the line 3-4, fig. 2; and

Figure 4, a sectional plan on the line 5-6, fig. 2.

Similar letters refer to similar parts throughout the several views.

A is the bottom plate of the stove, to which are secured suitable legs, *a a*, and on this plate rests the circular base *b* of the body *B*. *D* is the grate, beneath which and within the base *b* is the ash-chamber *E*, and in front of the latter is a suitable door or detachable plate, *d*. To the top of the body *B* is secured a cap, *F*, within which is the smoke-chamber *G*, the top plate *e* of the latter having a hole, *f*, for receiving a boiler or other cusinary utensil. The cap *F* has in front a projection, *h*, to which is hinged a door, *i*, the latter being adapted to an opening through which the fuel is passed into the body *B* of the stove. To the cap *F* is fitted the lower end of the cylindrical casing *H*, the top *j* of which has a circular boiler opening, *k*, the whole being surmounted with a detachable cover, *m*. The interior of the casing *H* is separated, by a horizontal partition, *n*, into an upper compartment, *J*, and lower compartment, *K*, the latter being an oven and the former a flue, both of which communicate with an exit pipe, *p*. Vertical partitions, *q q*, separate the oven *K* from the vertical flues *L L*, (figs. 3 and 4,) these flues forming communications between the smoke-chamber *G* in the cap *F* and the flue *J*. Suitable valves or dampers may be situated at the point where the oven communicates with the exit opening *p*, and where the latter communicates with the flue *J*. Access is had to the interior of the oven through an opening in front of the same, suitable curved doors, *t*, being arranged to slide in grooves in front of this opening. The body of the stove is of an oval or egg shape, and at its largest diameter there is a belt, *r*, on which rests an annular plate, *W*. Above this plate the body is so constructed as to have a number of flat sides, against which can be placed the faces of a number of sad-irons. Below the belt *r* the body of the stove gradually assumes a cylindrical form, the form best adapted for resisting the effects of the heat, which is most intense immediately above the grate *D*. It will thus be seen that the upper portion of the body of the stove is utilized as regards its applicability to receive a number of sad-irons without impairing the utility and durability of the lower portion, as the casing of the fire-chamber. The chamber *K*, after closing the doors *t*, becomes a convenient oven for baking, &c., on a small scale, and when the doors are open, and the cover of the opening *f* is removed, the chamber may be used for frying, broiling, or boiling, while the contents of a vessel placed over the opening *K*, above the flue *J*, (after the withdrawal of the cover *m*,) may be maintained in a boiling or nearly boiling condition; in fact, the stove is an economical disseminator of heat, and at the same time a cheap and serviceable cooking stove for small families, for the cabins of vessels, and for other places where a more costly stove would be out of place.

We claim as our invention, and desire to secure by Letters Patent—

The cast-iron body *B* of the stove, the upper portion of which has a number of inclined flat sides, and the

lower portion of which is cylindrical, in combination with the ring or ledge W, and with the cap F, cylindrical casing H, oven-chamber K, and flues L and J, the whole being arranged substantially as and for the purpose described.

In testimony whereof we have signed our names to this specification in the presence of two subscribing witnesses.

JOHN MARTINO,
JACOB BEESLEY,
JOHN CURRIE.
